CLAIM

The ornamental design for a tree stump grinding tooth, as shown and described.

DESCRIPTION

FIG. 1 is perspective view of a tree stump grinding tooth according to the present invention shown in use attached to the leading end of tool holder;

FIG. 2 is front perspective view of a tree stump grinding tooth according to the present invention;

FIG. 3 is rear perspective view of a tree stump grinding tooth according to the present invention;

FIG. 4 is a right side elevation view of the tree stump grinding tooth, the left side and top plan and bottom plan views being mirror images thereof;

FIG. 5 is a front elevation view of the tree stump grinding tooth;

FIG. 6 is rear elevation view of a tree stump grinding tooth; and,

FIG. 7 is a cross-sectional view as taken generally along lines 7-7 of FIG. 5 to better illustrate the ornamental contours of the front face of the tree stump grinding tooth. The broken lines in FIGS. 3, 4, 6 and 7 illustrate portions of the tree stump grinding tooth that form no part of the patented design. The broken lines showing the tool holder in FIG. 1 are provided for the purpose of illustrating environmental structure and do not form part of the claimed design.

1 Claim, 4 Drawing Sheets
